INVENTOR
Arthur Cox,
BY
William A. Smith, Jr.

ATTORNEY

UNITED STATES PATENT OFFICE.

ARTHUR COX, OF OLTON, NEAR BIRMINGHAM, ENGLAND.

CARBURETOR.

Application filed March 5, 1925. Serial No. 13,231.

To all whom it may concern:

Be it known that I, ARTHUR Cox, subject of the King of Great Britain, residing at "Harlech," Warwick Road, Olton, near 5 Birmingham, England, have invented a certain new and useful Carburetor, of which the following is a specification.

My invention has reference to carburetors of the kind described in the specification of 10 my United States Letters Patent dated the 31st day of August 1920 No. 1,351,624, wherein a nozzle discharges into a branch passage which conveys the fuel and the primary air into a main air-passage, and the 15 fuel-delivery from the said nozzle is varied by regulating an admission of air into the said branch by means of a rotary valve located between the nozzle and the main passage and operated by or from the throttle 20 valve.

The object of my said invention is to provide for the embodiment in a barrel-throttle carburetor of the above-mentioned type, of 25 an idling nozzle for supplying mixture to the engine when the throttle-valve is closed.

To realize this, I propose, according to 30 my present invention, to utilize the nozzle that discharges into the primary air-branch as the main or normal-running nozzle, and to provide an idling nozzle for delivering 35 fuel or mixture into the main passage on the engine side of the throttle valve when the main nozzle is out of action. Also I apply to or detachably mount upon the fixed member 40 or casing of the valve that controls the main nozzle discharge, a nozzle-housing in which both the main nozzle and the idling nozzle are fitted, whilst I also use in combination with such a nozzle system, a fuel 45 or mixture reception passage which is formed in the throttle chamber in concentric relation to the throttle axis and has communication, on the one hand, with the idling 50 nozzle by a conduit passage located outside the throttle-operated valve that controls the main nozzle, and on the other hand, with a system of ports formed in the throttle-barrel and adapted to deliver fuel from the 55 idling nozzle into the main passage on the engine side of the throttle when the latter is closed and during its initial opening movement.

Figure 1 of the accompanying drawings is 60 a vertical section of a carburetor embodying

the present invention and taken on line 1-1 of Figure 2.

Figure 2 is an elevation of that side of the carburetor on which the nozzle and the primary air-intake are located. 60

Figure 3 is a plan, partly in horizontal section on line 3-3 of Figure 4.

Figure 4 is an elevation of the carburetor looking from the right-hand side of Figure 2 and showing the engine side of the throttle-valve; this valve being in its closed position. 65

Figure 5 is a sectional elevation showing the fuel-connections between the idling nozzle and the engine side of the throttle; the 70 throttle being shown slightly opened.

Figure 6 is a vertical section on line 6-6 of Figure 5.

Figure 7 is a vertical section on line 7-7 of Figure 3.

Figure 8 is an enlarged sectional detail of 75 the idling nozzle.

Figure 9 is an elevation of the throttle-barrel separately.

The same letters of reference indicate 80 corresponding parts in the several figures.

In the construction illustrated, the part *a* (hereinafter referred to as the nozzle body) that houses the nozzles is detachably secured by screws or the like to a flange or seating *a'* on the outer end of the fixed 85 ported sleeve *a*² that surrounds the primary air branch *c* and contains the ported member *c'* of the valve which controls the fuel delivery of the nozzle *b* (hereinafter referred to as the main nozzle), and rotates 90 with the throttle-valve. Both the main and the idling nozzles *b*, *d* are removably mounted in chambers in the nozzle body, and the idling nozzle takes its fuel from a supply passage *e*² connected with the float chamber (not shown) of the device. The idling nozzle comprises a detachable and interchangeable nipple formed at the inner end of a screw threaded and axially-bored plug *d*²; the interior of said nipple having communication both with the idling fuel-passage *d*³ and with an air-intake hole *d*⁴ which is drilled in a cap *d*⁵ that is normally applied to the outer end of the plug. This nipple is also drilled with radial outlet passages *d*⁶ communicating with an annular clearance *d*⁷ that is provided between the nipple and its chamber *d*⁸, and with which an external conduit *e* of relatively small bore connects, the conduit *e* extending to 100 105 110

the throttle-chamber of the carburetor, where it communicates with a reception channel, groove or passage that is formed between an end of the throttle-barrel, and the 5 corresponding end of the throttle-chamber, in concentric relation to the throttle-axis. For instance, as in the illustrated construction, that end of the throttle-barrel f nearest the nozzle body is formed with an 10 annular step f' of smaller diameter than the throttle-chamber so as to provide an annular passage or reception chamber g into which the tube e leads so that this reception chamber is in communication with the externally-located idling nozzle in all 15 positions of the throttle.

From the reception chamber g , a hole h is drilled into the throttle barrel, parallel with the axis of the latter, and from this hole 20 one or more small ports lead out onto the periphery of the barrel on the engine side of the throttle.

In the device shown in the drawings, two such ports h' , h^2 are provided, and these 25 are so arranged that when the throttle is closed (see Figure 4) only the one port h' is uncovered and in communication with the induction passage on the engine side of the throttle barrel and it is from this port h' that 30 fuel is then induced from the idling nozzle by the depression set up by engine suction in the induction passage between the closed throttle and the engine. As regards the second port h^2 , this is uncovered or brought 35 into communication with the induction passage (as shown in Figure 5) by the initial movement of the throttle barrel from the full-closed position and its effect is to maintain the fuel supply from the idling 40 nozzle during such initial throttle opening and to prevent the cutting out of the idling nozzle before the main nozzle is in effective 45 operation. That is to say, when, with the engine idling, the throttle is slightly opened from the fully-closed position, the consequent opening of communication between 50 the atmosphere and the induction passage brings about a drop in the depression produced by engine suction within the said passage, but since both ports h' , h^2 are uncovered by the throttle movement, this reduced 55 depression is effective upon a port area double that which obtains when the throttle is closed, and by the action of the reduced depression on the doubled port area effective suction on the idling nozzle is maintained until the throttle is so far opened as

to bring the main nozzle into action. Irregular engine running during the change over from the idling to the main nozzle is thus 60 obviated.

Having described my invention, what I claim and desire to secure by Letters Patent is:—

1. A carburetor having a main body provided with a throttle chamber, a barrel type throttle rotatably fitted in said chamber, a primary air tube discharging into said throttle, a housing fixed on said tube, a main nozzle in said housing discharging into said tube, means for controlling the operation of the main nozzle including a rotary valve carried by the throttle, an idling nozzle in the housing, said throttle having an idling mixture discharge port and also having a 70 passage leading to said port, an idling mixture reception chamber concentric with the axis of the throttle and located between the end of the throttle and the throttle housing, said reception chamber communicating with said passage in the throttle, and a separate conduit having a small bore and extending between the idling nozzle and the reception chamber. 75

2. A carburetor having a main body provided with a throttle chamber, a barrel type throttle rotatably fitted in said chamber, a primary air tube discharging into said throttle, a housing fixed on said tube, a main nozzle in said housing discharging into said tube, means for controlling the operation of the main nozzle including a rotary valve carried by the throttle, an idling nozzle in the housing, said throttle having a plurality of idling mixture-discharge ports in its periphery, one of said idling mixture discharge ports being open to the engine side of the throttle when the throttle is closed and both of said idling mixture discharge ports being open to the engine side of the 90 throttle when the throttle is slightly opened, said throttle also having a passage leading to said ports, an idling mixture reception chamber concentric with the axis of the throttle and located between the end of the 95 throttle and the throttle housing, said reception chamber communicating with said passage in the throttle, and a separate conduit having a small bore and extending between the idling nozzle and the reception chamber. 100

In testimony whereof he hereunto affixes his signature.

ARTHUR COX.
